UNITED STATES PATENT OFFICE.

JOHN OWEN HARRISON, OF EVANSVILLE, INDIANA.

FENDER.

SPECIFICATION forming part of Letters Patent No. 759,707, dated May 10, 1904.

Application filed February 8, 1904. Serial No. 192,660. (No model.)

To all whom it may concern:

Be it known that I, JOHN OWEN HARRISON, a citizen of the United States, residing at Evansville, in the county of Vanderburg and State 5 of Indiana, have invented certain new and useful Improvements in Fenders; and I do hereby declare the following to be a full, clear, and exact description of the invention, such as will enable others skilled in the art to which 10 it appertains to make and use the same.

This invention relates to new and useful improvements in life-guards and fender combined, and is particularly applicable to street-car construction; and it consists in certain 15 features of novelty in the details of construction and arrangement thereof, all as will be hereinafter more fully described, and specifically pointed out in the claims.

In the annexed drawings, Figure 1 is an 20 elevational view, partly in section, of a street-car equipped with the improved device; and Fig. 2 is an inverted plan view of my improved device, partly broken away to better illustrate the construction thereof.

25 Referring to the drawings, A is a car-body. B is the front platform thereof.

C is the dashboard.

D is a fender locked upon the dashboard C by means of clips 1.

30 Supported beneath the body A is a scoop 2, which in the present instance is suspended from a bracket 3, by means of which it is pivotally supported. Slightly to the rear of the forward end of the scoop 2 is a roller 4, 35 upon which the scoop rests when dropped to the position indicated by the dotted lines in Fig. 1, wherein it will be noticed that the scoop 2 is supported upon the tracks E by means of said roller 4, with the advanced portion 5 of the scoop supported in such position 40 as to just clear the track-rail.

Connected with the lower portion of the platform B is a bracket 6, hereinafter referred to as a "car-bracket" for convenience of description, which bracket is duplicated at each side of the platform B and has supported therein the rockable shaft 7, upon which shaft are connected crank-arms 8, from the lower end of which extend links 9, and are thence con-

nected to the fender D by means of the inter- 50 posed bracket 10. (Best shown in Fig. 1.)

Supported by the platform B is the hanger 11, within which is pivotally supported at each side an independent hooked arm 12, which has a shoulder 13 at the lower end 55 thereof adapted to pass under and engage with the forward extension 5 of the scoop 2. Connecting the hooked arms 12 with the crank-arms 8 are links 14, whereby any motion communicated to the crank-arms 8 will be transmitted therefrom to the hooked arm 12. The hooked arm 12 is provided with a rearwardly-extending member 15, which may be integral therewith or may be a separate member secured thereto, but which is rockable there- 60 with upon the pivots 16 for the arms 12, which pivots are supported in the brackets 11.

Passing downwardly through the rearwardly-extending members or member 15 is a rod 17, provided at its lower portion with a 70 shoulder or offset, which may consist of the nut 18, screw-threaded thereon, or may be formed thereon in any manner, which shoulder 18 is designed for service as a support for the spring 19, which spring bears against the 75 lower face of the rearwardly-extending arm 15 and normally holds said arm up against the under side of the platform B.

Passing through the platform B at any convenient point with relation to the arm 15 is a 80 push-rod 20, designed to serve as a step whereby the lever 15 may be depressed from the car-platform, which push-rod is suspended in a normally elevated position by means of said spring 19, before referred to. The crank- 85 arms 8 are supported upon the shaft 7 and are locked thereto by means of the set-screws 21, so that the angularity of said crank-arms with relation to the platform B of the car may be changed at will within the limits of flexibility of the members connected therewith.

The operation of the device is as follows: The fender D being yieldingly supported at its lower end by means of the elements here- 90 fore referred to, it will be obvious that contact therewith which will be sufficient to disturb the normal position of the lower portion of said fender will cause a rocking of the shaft

7 through link 9 and crank-arms 8, thereby projecting the link 14 forwardly or toward said fender D, thereby releasing the shoulder 13 from its engagement with the forward exten- 5 tension 5 of the scoop 2, whereupon said scoop will drop by gravity to the position shown in dotted lines in Fig. 1. If it is desired to lower the scoop from the platform of the car before collision, all that is necessary is to bear upon the push-rod 20, thereby depressing the arm 15 and rocking the crank-arm composed of the members 15 and 12, and thereby release the scoop.

I am aware that minor changes in detail, 15 construction, and operation of parts may be made and substituted without departing from the spirit of my invention, and it is my intention to claim such changes except as herein- after specifically limited in the claims.

20 Having now described and ascertained the nature of my said invention, what I claim, and desire to secure by Letters Patent, is—

1. In a device of the character described, a fender, a car-bracket, a rockable shaft sup- 25 ported thereby, crank-arms on said shaft, links connecting said fender and crank-arms, a scoop, and a spring-actuated scoop-supporting means pivotally connected with said crank- arms.

30 2. In a device of the character described, a fender, a scoop, a car-bracket, a rockable shaft supported thereby, crank-arms on said shaft, independently-supported crank-arms with rearwardly and downwardly extending mem- 35 bers, spring-supports for said rearward exten- sion, rearwardly-projecting scoop-supporting hooks on said downwardly-extending mem- bers, and a push-rod adapted to rock said in-

dependently-supported crank-arms to release said scoop.

3. In a device of the character described, a fender, a scoop, a car-bracket, a rockable shaft supported thereby, crank-arms on said shaft, a pivotally-supported scoop-engaging mem- 45 ber, a spring-support for said member, and means whereby said scoop may be released therefrom from the car-platform and from contact with said fender.

4. In a device of the character described, a fender, supporting-brackets in proximity 50 thereto, a rockable shaft supported by said brackets, crank-arms on said shaft, pivotally and independently-supported crank-arms having substantially horizontally extending por- 55 tions, supporting-springs for said portions, and means whereby both sets of crank-arms may be rocked from the car-platform and from the fender.

5. In a device of the character described, a yieldingly-supported fender, a pivotally-sup- 60 ported scoop having an end extension, a sup- porting-roller carried thereby, a supporting- bracket, a rockable shaft carried thereby, crank-arms on said shaft, links from said crank-arms to said fender, rockable crank- 65 arms, hooks thereon engaging said scoop, sup- porting-springs for said crank-arms, and a push-rod bearing on one of said arms adapted to release said scoop.

In testimony whereof I hereunto affix my 70 signature in presence of two witnesses.

JOHN OWEN HARRISON.
